CLAIM

The ornamental design for a stand for television receiver as shown and described.

DESCRIPTION

1.1 : Front perspective

1.2 : Back perspective

1.3 : Front

1.4 : Back

1.5 : Left

1.6 : Top

1.7 : Bottom

1.8 : Reference

This article is a stand for television receiver provided with a pocket on the backside thereof; reproduction **1.8** illustrates a use of the back pocket that forms no part of the claimed design; a right view is omitted because it is a mirror image of the left view; the broken lines shown in the reproductions depict portions of the stand for television receiver that form

(Continued)

no part of the claimed design; the shading lines are used to show the surface of the claimed design and do not represent its surface ornamentation.
